John P. Ellis

United States Patent Office.

JOHN P. ELLIS, OF FLUSHING, NEW YORK.

Letters Patent No. 73,085, dated January 7, 1868.

IMPROVEMENT IN WATER-PROOF SAFE.

The Schedule referred to in these Letters Patent and making part of the same.

TO ALL WHOM IT MAY CONCERN:

Be it known that I, JOHN P. ELLIS, of Flushing, in the county of Queens, and State of New York, have invented a new and improved Water-Proof Safe; and I do hereby declare that the following is a full, clear, and exact description of the same, reference being had to the accompanying drawings, which form part of this specification.

It is very desirable to deposit in some secure place of concealment, valuable papers, bonds, &c., and this is often desirable when ordinary safes are employed, for such safes usually receive the burglar's first attention. The object, therefore, of my invention is to provide a water-proof safe, in which papers, bonds, &c., &c., can be enclosed, which water-proof safe can be buried in the ground, dropped in a cistern, or deposited in some other place where the owner shall know its position, and where its hiding-place will not be likely to be discovered—a safe so constructed, that the papers enclosed therein shall be absolutely protected from dampness.

My invention consists in a case provided with one or more inner cases or bags, in which papers, bonds, and other valuable documents can be enclosed and secreted in the ground or elsewhere, without danger of the papers, &c., becoming destroyed, as will be hereinafter specified. In the accompanying drawings—

Figure 1 is a central longitudinal section of my invention, taken on the plane of the line xx , fig. 3.

Figure 2 is an external view of an inner case.

Figure 3 is a transverse vertical section, taken on the plane of the line yy , fig. 1.

A designates the outer case, having one end closed and the other open. B is a cap or cover, one end of which, in the present instance, is provided with a small screw, which fits into a female screw, cut in the open end of the case A. Rubber or any other suitable packing, p, may be employed to insure a perfectly water-tight joint, and to prevent water creeping in to rust the screw, or getting into the case. In the present instance, I have shown the case A and its cover B as made of cast iron, but I will remark that any other suitable material may be employed for both these parts.

C is the inner case, and D is its cover, both of which I have shown as constructed of tinned sheet metal, but which may be of any other suitable material. The cover D, I have shown as of a length to nearly surround the whole case C, by which I think I am insured greater security against water or other fluid creeping in, but I do not confine myself to any particular length of cover or cap D, nor to a cap sliding over the case, nor to the case sliding over the cap.

E is a bag for holding the documents to be preserved. It is made of water-proof material, in the present instance, and is so constructed that its end may be tied up, and a cap, b, of suitable water-proof material, be secured over the tied-up end, as shown in fig. 1. This cap insures greater security against dampness creeping in to the papers, and may or may not be used, as occasion may require.

Upon the inside of the case A B, fenders, a, are provided, which serve to keep the inner case C D from lying against the inner surface of the said case A B. A chamber or space being thus provided between the two cases, there is little liability of mildew, mould, &c., between the cases, as would be likely to occur if the inner case should lie for any length of time in contact with the outer case. As an equivalent means for the same purpose, I have shown fenders, c, (see fig. 2,) secured to the outside of the inner case.

It will be noticed that the papers, bonds, or other valuable documents, are to be placed in the bag E, and tied up, and, if thought advisable, the cap a secured over the drawn-up end. The bag E is then placed in the case C, and the cover D shoved on it; the case C D is then placed in the case A, and the cover B secured to the case A.

This safe can be buried in the ground, or let down into a well or cistern, or placed elsewhere, and the papers enclosed in it be perfectly free from mildew, mould, and other destroying elements occasioned by dampness.

The safe, as above described, is composed of three parts, to wit, the outer case, the inner case, and the bag; but I wish it understood that I do not limit my invention to the employment of all three parts together. For instance, the outer case and the bag may be used without the inner case; the inner case and the bag may be used without the outer case; and the two cases may be used without the bag. The safe when thus constructed would be efficient if placed in a damp place, such as a vault, basement, foundation-wall, &c.; but when the safe is to be buried in the ground or submerged in water, I prefer to use all three parts, that is, two cases and

a bag; and I do not limit myself to the shape of the cases or bag, nor to the material of which the latter may be made. Should the enclosing case be made of wood, or have some buoyant quality, which would sustain it on the surface of the water, the safe would be well-adapted for containing ships' papers.

What I claim as my invention, and desire to secure by Letters Patent, is—

A water-proof safe or receptacle for papers and other valuable documents, constructed substantially as herein specified.

JOHN P. ELLIS.
